UNITED STATES PATENT OFFICE.

JOHN ROGERS, OF NEW CANAAN, CONNECTICUT.

DESIGN FOR A GROUP OF STATUARY.

SPECIFICATION forming part of Design No. 14,594, dated January 29, 1884.

Application filed November 24, 1883. Term of patent 14 years.

To all whom it may concern:

Be it known that I, JOHN ROGERS, a citizen of the United States, residing at New Canaan, in the county of Fairfield and State of Connecticut, have invented and produced a new and original Design for a Group of Statuary, of which the following is a specification, reference being had to the accompanying photographic illustrations, forming part thereof.

10 The group shows two ladies who have come late to church. They each hold a book in their hands. The younger one is standing up and partly turning round toward the gentleman in the pew behind her, who is showing

15 her the hymn in his book, while the elder lady, who is sitting down, looks up at them with an expression of annoyance at the prefer-

ence shown. A boy in the pew in front of the ladies is reclining on the cushion, and is putting on his father's hat and gloves.
